UNITED STATES PATENT OFFICE.

CHARLES G. SMITH, OF WASHINGTON, DISTRICT OF COLUMBIA, ASSIGNOR TO CHARLES FISCHER, OF BROOKLYN, NEW YORK

MAGNETIC SPEEDOMETER.

1,312,082.

Specification of Letters Patent.

Patented Aug. 5, 1919.

Application filed August 8, 1918. Serial No. 248,984.

To all whom it may concern:

Be it known that I, CHARLES G. SMITH, a citizen of the United States, and a resident of Washington, District of Columbia, have 5 invented certain new and useful Improvements in Magnetic Speedometers, of which the following is a specification.

In my prior Patent 1,207,647 of December 5, 1906, I have described a magnetic speedometer characterized by constant intensity of magnetization and consequent uniformity of torque, and in a copending application Serial No. 248,983, filed August 8, 1918, I have disclosed certain features of construction and relation whereby this principle is rendered applicable to or may be approximated in speedometers having rotating magnets with eccentric or traveling fields. The present application sets forth another valuable specific form of the invention generic to the two applications and claimed broadly in the other case. In the construction set forth herein both members of the magnetic circuit rotate, and various other distinctive 20 features are included, as will hereinafter appear. In general, the object is to provide another efficient design adapted to embody the principles set forth in my other specifications.

30 In the accompanying drawings:

Figure 1 is a central vertical section;

Fig. 2 is an enlarged horizontal section on the line 2—2 of Fig. 1;

Fig. 3 is an elevation of the conductor 35 cup;

Fig. 4 is a fragmentary sectional plan; and

Fig. 5 is a fragmentary perspective view of the armature.

40 The instrument may be contained in an upright circular case 1 having an upper window 2 through which the speedometer indication is visible, and lower windows 3 behind which odometer indicators 4 may be located. A hub 5 is mounted rotatably upon the upwardly projecting portion of a fixed axle 6 rising from a frame portion 7 within the casing. The bottom of this hub has internal beveled gear teeth 8 meshed by a

beveled driving pinion 9 on an inclined 50 shaft 10, which passes through the rear wall of the casing.

The rotating magnet 11 is preferably of a circular horseshoe type, with its poles at one and the same side of the axis of rotation, 55 and is suitably fixed on the hub, which may have a basal flange 12 for the magnet to rest upon. In the particular form illustrated an underframe 13 is interposed between the magnet and flange, all being held 60 rigidly together, and this frame serves as a support for an armature 14 constituting the other member of the magnetic circuit, and which is thus coupled with the magnet to rotate therewith.

65 The armature 14 is preferably short so as merely to overlap the gap between the north and south poles of the magnet, and preferably, also, it lies at the outer side of the magnet and substantially in its plane. The 70 armature may or may not itself be a magnet, but preferably it is made of soft iron.

One or both of the members of the magnetic circuit are provided with series of concentrating teeth 15. It is sufficient, however, 75 that they be formed on the ends of the armature which are opposed to the polar ends of the magnet. The central or intermediate part of the armature is without teeth. For the reasons explained in the aforesaid co- 80 pending application it is advantageous to laminate the teeth; and in the present case this is most conveniently effected by building up the entire armature of strips, comprising toothed strips 16 and plain spacer 85 strips 17, both of magnetic material, the whole being riveted together and to the support.

The space between the armature and magnet is for the reception of an oscillatory conducting annulus 18, preferably formed by the depending flange of a cup. This flange is of copper, or of some alloy having a lower temperature coefficient, and is slotted by vertical slots 19, which extend to the lower 90 edge of the flange, where they are electrically open. As explained in my other application, the region bars 20 between the slots

should be as narrow as practicable, but are materially wider than the slots and preferably about twice as wide as the concentrating teeth.

- 5 The upper part of the cup, above the magnetic field, may be made in a separate piece or crown 21, which need not be of conducting material, and which, not requiring to be slotted, may bear directly on it
 10 the indicator characters which are visible through the window 3.

- The conductor and indicator cup is supported by a staff 22, which has bearings in the top of the axle 6 and in a bracket 23.
 15 The spring which resists the drag upon the conductor is indicated at 24.

- As illustrated, the indicator crown 21 may be made wider than the slotted conductor flange or annulus 18, so as to overhang the
 20 armature and bring the characters close to the window.

In operation, the eddy currents set up in the conductor are not dependent upon the strength of the permanent magnet, and
 25 neither is the torque, so long as the magnet is stronger than a value sufficient to saturate the teeth 15. This is true if the slots in the conductor are open and if the magnetizing field is substantially uniform over a
 30 bar as large or larger than a region 20. Furthermore, it is important that the teeth be narrower than the regions 20. It will be understood, therefore, that eddy currents are produced within each region 20 as a
 35 tooth passes it, but the general field does not produce eddy currents, because the slots 19 prevent circulation across them, and these particular currents must pass across or around the slots or not exist. The general
 40 magnetic field is composed of all the lines of force emanating from and entering the north and south poles of the magnet, and since these are much wider than the regions 20, the only effect of the travel of the poles
 45 as a whole past the regions is to create a difference of potential between the inner and outer portions of the regions, and as the latter are not connected in closed circuit with each other a resulting current can
 50 not pass. Hence the chief currents generated in the conductor are due to the excess magnetism of the teeth 15 over and above the general magnetism. This excess magnetism I shall call $4\pi I$, following the usual
 55 notation; the general magnetism I shall call H after the customary notation. If now the field H is more than strong enough to saturate the teeth, then I, the intensity of magnetization of the teeth, remains a constant
 60 maximum value. Any increase or decrease of H, due to any change in the strength of the magnet, does not affect I so long as such changes lie in a range above that value of H which saturates the teeth. Consequently
 65 the torque is uniform.

What I claim as new is:

1. In a magnetic speedometer, the combination of two members of a magnetic circuit coupled and mounted so that both rotate and having poles at one side of the axis 70 of rotation so as to produce a traveling field, one of said members being provided with a series of concentrating teeth, and an oscillatory conductor slotted transversely to the circumferential direction with open slots, 75 the width of the regions or bars between the slots being greater than that of the teeth, whereby the teeth set up eddy currents within said bars.

2. In a magnetic speedometer, the combination of an approximately circular horseshoe magnet, a short armature spaced from and spanning the gap of the magnet, one of said members being provided in its portions opposed to the other with series of 85 concentrating teeth, means uniting the said members in the stated relation and permitting their rotation, and an interposed oscillatory conductor slotted transversely to the circumferential direction with open slots. 90

3. In a magnetic speedometer, the combination of a horseshoe magnet, a short armature spaced from the poles of the magnet and provided with a series of concentrating teeth, means coupling and mounting said members for rotation, and an interposed oscillatory conductor provided with open slots transverse to the direction of movement, the width of the regions or bars between the open slots being greater than that 100 of the teeth.

4. In a magnetic speedometer, the combination of a horseshoe magnet, a short laminated armature spaced from the ends of the magnet and provided with a series of concentrating teeth, means coupling and mounting said members for rotation, and an interposed oscillatory conductor provided with open slots transverse to the direction of movement, the width of the regions or 110 bars between the open slots being greater than that of the teeth.

5. In a magnetic speedometer, the combination of a horseshoe magnet, a short armature spaced from and spanning the gap in 115 the magnet, one of said members being provided on its portions opposed to the other with series of concentrating teeth, and an interposed conductor cup having its flange slotted with open slots. 120

6. In a magnetic speedometer, the combination of a horseshoe magnet, a short armature spaced from and spanning the gap in the magnet, one of said members being provided on its portions opposed to the other with series of concentrating teeth, means for coupling and rotating both members, and a conductor cup having its interposed flange slotted with open slots and an indicator crown above its slotted portion. 130

7. In a magnetic speedometer, the combination of a horseshoe magnet, a short armature spaced from and spanning the gap in the magnet, one of said members being provided on its portions opposed to the other with series of concentrating teeth, means for coupling and rotating both members,

and a conductor cup having its interposed flange slotted to its edge, where the slots are open, the regions between the slots being wider than the teeth.

In testimony whereof, I have signed my name to this specification.

CHARLES G. SMITH.
